UNITED STATES PATENT OFFICE.

JOHANNES FRANCISCUS SCHLEPER, OF AMSTERDAM, NETHERLANDS.

METHOD OF AND MEANS FOR JOINTING ELECTRIC-CURRENT CONDUCTORS.

1,419,523.

Specification of Letters Patent. Patented June 13, 1922.

Application filed April 20, 1922. Serial No. 555,697.

To all whom it may concern:

Be it known that I, JOHANNES FRANCISCUS SCHLEPER, a subject of the Queen of the Netherlands, residing at Amsterdam, Netherlands, have invented certain new and useful Improvements in and Relating to Methods of and Means for Jointing Electric-Current Conductors, of which the following is a specification.

10 My present method of jointing electric current conductors is characterized by this, that the naked ends of the wires are contorted and then twisted into a metallic case or sleeve provided internally with conical or equivalent screw thread, and that said case is insulated by a cap of suitable material. As to the insulating cap, this may, for instance, have a screw connection with the case so that when the contorted wire ends are 20 twisted into the case the latter cannot turn with respect to the cap.

The annexed drawing illustrates the said invention, Figure 1 being a longitudinal sectional view of a suitable form of my novel 25 means, Figure 2 being an elevational view thereof at a reduced scale.

The illustrated means comprise an externally conical open ended brass case 1 with internal conical screw thread. Said 30 case fits into an insulating cap 2 and is provided near its open end with ordinary external screw thread for receiving internal screw thread of the cap 2.

The naked wire ends are contorted to form 35 a joint 3 which is then twisted into case 1 covered by cap 2. Within certain limits it is immaterial how great the diameter of the joint 3 is, for owing to the taper of the screw thread in the case 1 this thread always engages the joint 3 at a greater or a 40 smaller distance from the open end of case 1. It is therefore clear that when the contorted wire ends are twisted with sufficient force into the case 1 a reliable contact is established and that the screw thread in case 1 45 cuts a corresponding thread in the wire ends. If desired I may then solder the joint.

During the insertion and tightening of

the wires into case 1 the latter cannot turn with respect to the cap 3, provided of course 50 that it has been tightly screwed thereinto. The bottom of the case 1 prevents the insulating cap 3 from being damaged by the ends of the wires.

Owing to the taper of the internal screw 55 thread of case 1 I may use cases of the same type and size for jointing two, three or more wires of different gauges.

As a matter of course it is not necessary 60 for the internal screw thread to be exactly conical, but it is essential that said thread is tapered. That is to say, the inner wall of case 1 may be formed by a coaxial series 65 of cylindrical walls of gradually decreasing diameter, each provided with screw thread.

The screw connection between the case 1 and the cap 2 could be replaced by any other connection adapted during the insertion and tightening of the contorted wire ends to prevent rotary motion of the case in respect 70 to the cap.

By splitting the case 1 as indicated in dotted lines in Fig. 1 I may ensure increased clamping action of the case 1 on the wire ends.

Claims:

1. A process for joining electric current conductors which comprises contorting the bare wire ends and then twisting such wire ends into a metallic case having internal 80 screw threads of decreasing diameter so that the threads of the case cut into and secure the wire ends.

2. A means for joining electric current conductors, comprising a metallic case having a conical internal screw thread into which the bared ends of the conductors are held by twisting, and an insulating cap fitting on said case.

3. A means as claimed in claim 2, in which 90 means is provided between the cap and case for preventing the latter from turning when the ends are twisted into the case.

In testimony whereof I affix my signature.

JOHANNES FRANCISCUS SCHLEPER.
